UNITED STATES PATENT OFFICE.

RUDOLF WEIDE, OF BERLIN, GERMANY, ASSIGNOR TO THE FIRM HERMANN HURWITZ AND CO., OF BERLIN, GERMANY.

TRANSFER-PRINTING APPARATUS.

Application filed August 31, 1925, Serial No. 53,695, and in France September 8, 1924.

This invention relates to a known transfer printing device such for example as the device known as the so-called "opalograph" system. In the case of this transfer apparatus the plate containing the printing set is carried by a bed. The printing set is inked by means of cylinders, then the sheet to be printed upon is placed in position, and finally the printing is effected by means of a printing cylinder.

According to the invention the printing cylinder and the inking cylinder are journaled in a frame constructed as a sliding carriage, in such a way that by means of a simple handle the inking of the printing set can be effected during the travel of the slide in one direction and the printing during the return movement, a sheet of paper having in the meantime been placed in position.

One example of the construction of the invention is illustrated in the accompanying drawing.

Figure 1 is a side elevation.

Figure 2 a plan, and

Figure 3 an end elevation.

Fig. 4 is a fragmentary plan view of the inking and printing cylinders and cooperating parts.

Fig. 5 is a detail section on the line 5—5 of Fig. 4.

On a base plate 1, which may for example be adapted to be secured by means of clamping screws to a table or the like, rests a bed 2, which constitutes or contains a printing set. This part of the apparatus need not be described in detail. A slide or carriage 3 is supported on rollers 4 on the base plate 1 to enable it to travel along the latter. In the slide frame 3 rests a shaft 5, about which two arms 8 are adapted to oscillate, the said arms being united at the top by a cross-bar 6, provided with a handle 7. The arms 8 carry the printing cylinder 10 and the inking cylinder 11. The cylinders 10 and 11 carry pinions 12 and 13 which are connected with one another by intermediate wheels 14 and 15. In the slide frame is also supported an inking mechanism, of which only the ink-distributing cylinder 16 is shown.

At the side of the printing cylinder 10 one of the arms 8 carries another roller 18, which during the movement of the carriage

towards the right of the drawing, runs on to a rail 19. The drawing shows a second rail 20 at the left-hand side of Figure 1. This rail coats with a roller 22 which is rigidly connected to the shaft of the printing cylinder 10, as is most clearly shown in Figure 4. A coil spring 21 on the shaft 5 tends to keep the parts in the position shown in the drawing.

The apparatus operates in the following manner:—

Figure 1 shows the printing position, in which the slide is being moved towards the right by means of the handle 7. The printing cylinder 10 remains in the position shown until the roller 18 is raised by running up on to the rail 19. The sheet is removed from the bed 2 and the user now pushes the slide towards the left by means of the handle 7. In doing this the user raises the handle 7 in such a way that the inking cylinder 11 comes to bear upon the printing set of the bed 2. The slide is now in this position moved towards the left, and during this movement the roller 22 runs up on to the rail 20. This has for its object to prevent the printing cylinder 10 during the return movement of the slide to the right from coming into contact with the edge of the left-hand side of the bed and thereby becoming damaged and to ensure a smooth application of the printing cylinder to the bed. After a sheet has now been placed in position again the slide is returned and the cylinder 11, which has travelled back into the position shown in Figure 1, then takes up ink again.

Owing to the action of the spring the cylinders 10 and 11 are always held in such a way that the printing cylinder 10 is located in the working position.

Thus in order to cause the inking cylinder 11 to bear upon the printing set the worker must displace the set of cylinders against the action of the spring 21. The spring, however, prevents the inking cylinder 11 from being moved by accident or carelessness over a paper laid upon the printing set 2.

What I claim is:—

Transfer printing apparatus comprising a printing set, a frame adapted to be reciprocated over the printing set, rockably sup-

ported arms mounted on said frame, a printing cylinder and an inking cylinder journaled in said arms, toothed wheels connecting said cylinders to one another, a handle secured to the cylinder-carrying arms, said handle serving for reciprocating the frame, and for bringing the printing and inking

cylinders alternately into their operative positions and a spring constantly tending to keep the printing cylinder in its operative ¹⁰ position.

In testimony whereof I have signed my name to this specification.

RUDOLF WEIDE.
